UNITED STATES PATENT OFFICE.

JOHN KERSHENSTEIN, OF JOHNSTOWN, PENNSYLVANIA.

RAILWAY FROG.

Application filed August 23, 1922. Serial No. 583,828.

To all whom it may concern:

Be it known that I, JOHN KERSHENSTEIN, citizen of the United States, residing at Johnstown, in the county of Cambria and 5 State of Pennsylvania, have invented certain new and useful Improvements in Railway Frogs, of which the following is a specification.

This invention relates to an improved 10 railway frog and seeks, as one of its principal objects, to provide a frog which will form a safe and rigid connection between the rail ends coacting with the frog.

The invention has as a further object to 15 provide a frog wherein jolting of rolling stock passing thereover will be minimized.

And the invention has as a still further object to provide a frog which may be readily installed.

20 Other and incidental objects will appear hereinafter.

In the drawings:

Figure 1 is a plan view showing my improved frog in conjunction with a railway 25 switch,

Figure 2 is a perspective view of the frog,

Figure 3 is a bottom plan view of the device, and

Figure 4 is a transverse sectional view on 30 the line 4-4 of Figure 1.

In carrying the invention into effect, I employ a block 10 flared or widened from a point medially thereof toward its ends. The block is, as shown in Figure 2 of the drawings, provided with a flat upper face and at one side edge is formed with an upstanding tread rib 11 and an angularly disposed guard rib 12 while at its opposite side edge the block is provided with a similar tread 40 rib 13 and angularly disposed guard rib 14, the ribs conforming to the outline of the side edges of the block. Upstanding from the upper face of the block between the diverging ends of the ribs 11 and 13 is a medially disposed 45 double-ended frog point 15 substantially diamond shaped in contour and upstanding from the upper face of the block between the diverging ends of the guard ribs 12 and 14 is a medially disposed triangular shaped frog point 16. Intersecting flangeways 17 and 18 are thus defined between the frog points, the tread ribs 11 and 13 and guard ribs 12 and 14, and at the ends of these flangeways the upper face of the 55 block is cupped to provide entrance depressions 19. Formed in the adjacent end of the

block to aline with the tread ribs 11 and 13 are slots 20 defining longitudinally directed tongues 21 which form the outer side walls of said slots. These slots are provided with 60 flat vertical inner end walls 22, it being noted in this connection that the adjacent ends of the tread ribs 11 and 13 provide continuations of said walls, and formed in the lower side of the block at said slots are seats 23 65 to accommodate the base flanges of rails fitting in said slots.

Extending from the base end of the frog point 16 is an upstanding tail rib 24 and projecting from the adjacent end of the 70 block is a triangular shaped extension 25 lying medially between the diverging ends of the guard ribs 12 and 14. The upper face of the extension as well as the upper face of the tail rib 24 lie flush with the frog point 75 16 and formed in the block at one side of said extension is a slot 26 at the outer end of which the block is provided with a tongue 27 lying in spaced parallel relation to the adjacent face of the extension. The slot 26, 80 like the slots 20, is provided with a flat vertical inner end wall and, as will be observed, the tail rib 24 as well as the upper side of the extension are cut away to define a rail tread seat 28 terminating at the base end 85 of the frog point, the base end of the frog point forming a continuation of the inner end wall of said slot. Formed in the lower side of said extension as well as in the lower side of the block is, as shown in Figure 3, a 90 seat 29 to accommodate the base flange of a rail fitting in the slot 26. Formed in the extension in alinement with the base end of the tail rib 24 is a slot 30 defining a tongue 31 forming the outer side wall of said slot. 95 The extension is cut away at its upper side to provide a seat 32 for the tread of a rail fitting in said slot and is likewise cut away at its lower side to provide a seat 33 for the base flange of the rail. The slot 30, like the 100 slot 26 is provided with a flat vertical inner end wall and the base end of the tail rib 24 provides a continuation of said wall.

In Figure 1 of the drawings, I have shown my improved frog in connection with a railway switch. Fitting in one of the slots 20 of the block to aline with the tread rib 11 is a rail 34 and fitting in the slot 26 of the block to aline with said rail is a rail 35, the rails 34 and 35 forming a part of the main 110 track, a parallel rail of which is indicated at 36. Fitting in the other of the slots 20

of the block is a rail 37 and alining with said rail is a rail 38 fitting in the slot 30 of the extension 25 of the block. The rails 37 and 38 form a part of the switch track, a parallel rail of which is indicated at 39. Extending through the tongue 21, through the rails 34 and 37, and through the adjacent end of the block, are bolts 40 securing said rails to the block. Extending through the rail 35 and through the inner end of the extension 25 is a bolt 41 and extending through said extension and through both of the rails 35 and 38 are bolts 42, the bolts 41 and 42 rigidly connecting these latter rails with the block. As suggested in Figure 4, the slots 20, 26 and 30, are formed to snugly accommodate the ends of the rails engaging therein while the end faces of the rails abut flat against the end walls of said slots. At the same time, the treads of the rails 35 and 38 are snugly accommodated in the seats 28 and 32 while the base flanges of these rails as well as the base flanges of the rails 34 and 37 snugly fit in the seats 23, 29 and 33. Tight joints between the ends of the rails and the block are thus provided.

Having thus described the invention, what is claimed as new is:

1. A railway frog including a block having intersecting flangeways and provided at one end between said flangeways with an upstanding frog point and at its opposite end between the flangeways with an upstanding double-ended frog point.

2. A railway frog including a block having intersecting flangeways and provided at one end between said flangeways with an upstanding frog point and at its opposite end between the flangeways with an upstanding double-ended frog point, the latter end of the block being formed at opposite sides of said double-ended frog point with slots to accommodate the ends of rails.

3. A railway frog including a block having intersecting flangeways and provided at one end between said flangeways with an upstanding frog point and at its opposite end between the flangeways with an upstanding double-ended frog point, the latter end of the block being formed at opposite sides of said double-ended frog point with

slots to accommodate the ends of rails and the former end of the block being formed with a like slot arranged in alinement with said first mentioned frog point. 55

4. A railway frog including a block having intersecting flangeways and provided at one end between said flangeways with an upstanding frog point and at its opposite end between the flangeways with an upstanding double-ended frog point, the block being provided at the former end thereof with an extension formed to accommodate rail ends lying at opposite sides of the extension and being provided in alinement 65 with one side of said extension with a slot to receive one of said rail ends. 60

5. A railway frog including a block having intersecting flangeways and provided at one end between said flangeways with an upstanding frog point and at its opposite end between the flangeways with an upstanding double-ended frog point, the block being provided at the former end thereof 70 with an extension having a slot to accommodate a rail end and the block being formed at one side of said extension with a like slot to accommodate a second rail end extending in alinement with said first mentioned frog point. 75

6. A railway frog including a block having intersecting flangeways and provided at its ends between the flangeways with upstanding frog points, the block being formed at one end with a slot opening through the 85 bottom face of the block and extending in alinement with one of said frog points and said frog point being provided with a tail rib flanking said slot and coacting with the outer end edge of said frog point to define an angular rail tread seat. 90

7. A railway frog including a block having intersecting flangeways and provided at its ends between the flangeways with upstanding frog points, the block being formed 95 at one end with an extension and the block as well as said extension being provided with tongues to overlie rail ends secured to said extension and the block.

In testimony whereof I affix my signature.

JOHN KERSHENSTEIN. [L.S.]
